CARBURETOR OR THE LIKE

Raymond W. Litzinger, Pittsburgh, Pa., assignor
of twenty-five percent to Lee C. Newsome,
Minneapolis, Minn., and twenty-five percent
to Richard H. Newsome, Bellevue, Pa.

Application May 26, 1934, Serial No. 727,700

10 Claims. (Cl. 261—107)

The present invention relates to improvements in carburetors or the like in which air is mixed with vapor resulting from the evaporation of a volatile liquid such as alcohol, gasoline, kerosene, naphtha, and the like, the object being to improve the carbureting, co-mingling, and drawing capacity of the apparatus so that a drier, better, and more constant quality of mixture than is obtained with the apparatus hitherto in general use for the purpose.

I provide a simple, convenient, inexpensive, and efficient form of carburetor which may be employed for the production of a gaseous inflammable mixture suitable for lighting and heating purposes, and it may also be used for supplying a fuel mixture to internal combustion engines. Likewise it is applicable to other purposes where an intimate mixture of a volatile liquid and a gas is to be produced.

In the drawing,

Figure 1 shows a cross section of my device;
Figure 2 shows a plan view with the top removed;

Figure 3 is a section along the line III—III of Figure 2 with the top in position; and

Figure 4 is a view in perspective of a beater employed in the apparatus.

The carburetor in general comprises a sheet metal reservoir or receptacle 2 for the volatile liquid to be evaporated, the receptacle being preferably elongated and flat, of substantially rectangular shape, and provided with a tightly fitting top plate or cover 3 having a flange 4 to closely fit over the sides and ends of the receptacle. The top 3 may be secured in place by soldering or welding or it may be made so that it is held in place by friction.

From one end of the reservoir or casing 2, an inlet pipe 5, having a valve 6, projects. This pipe connects to a source of air pressure (not shown). Surrounding the intake is a baffle 7 of sheet metal which is secured to the end wall of the receptacle and contacts the top plate 3 and terminates a short distance from the bottom of the receptacle. Any air admitted through pipe 5 must pass around the bottom of this baffle.

Arranged in vertical position in the receptacle at suitable spaced positions, are a plurality of partitions 8 of thin sheets of pumice stone or similar material, preferably of a non-fibrous, ceramic, or earthen character, having very fine pores therethrough. I have found that partitions made out of thin sheets of pumice stone serve to break up the tiny globules of liquid. At the same

time, the air is separated into tiny streams in forcing its way through the pumice. This brings the air and the broken-down globules of liquid into intimate contact, giving a complete and thorough diffusion with the result that the gas issuing from an apparatus in which such a filter or partition is used is an extremely dry gas and one that has superior qualities. The margin of these partitions contact the top and side walls of the reservoir so as to be air tight. The partitions 8 have portions 9 cut away from the bottom (see Figure 3) so that passages are provided beneath the lower edges of the partition and the bottom of the receptacle.

Spaced between the partitions 8 are partitions 10 or wicks of absorbent material such as ordinary cotton wicking supported on a metal frame. These partitions contact the side walls and top of the reservoir and extend almost to the bottom of the receptacle. Mounted on the sides of the reservoir are a series of beaters 11, one for each of the absorbent partitions 10. The beaters are located to the side of the partition nearest the inlet pipe and near the top of the receptacle. These beaters 11 are formed of thin sheet material 12 and have a wire 13 extending along the sides and bottom, the ends of the wire 14 being shaped to form journals which hinge on the side wall of the receptacle. The air passing through the receptacle causes the beaters to strike against the adjacent absorbent partitions and causes any drops of liquid which have accumulated thereon to be jarred off. A baffle 15 of sheet material is provided adjacent the vapor outlet 16 to prevent direct entrance of the vapor. The vapor outlet pipe or discharge pipe 16 leads to the point where the gas is to be used and has therein a control valve 17.

On one side of the device and preferably near the inlet end, a filling device 18 is provided for keeping the receptacle supplied with a volatile fluid. The filling device or fuel tank 18 connects with the receptacle through a pipe 19, the outlet of which terminates in the receptacle 2 at the level at which it is desired to maintain the fluid therein.

In the operation of the apparatus, the receptacle is supplied with fluid until the absorbent wicks 10 are saturated and the liquid assumes the predetermined level. As long as it is desired to generate gas, air is introduced through the inlet pipe 5 and allowed to pass through the receptacle, as shown by the arrows in Figure 1, and is led to the desired point by discharge pipe 16. The air from the inlet pipe will follow the

paths shown by the arrows in Figure 1 through the saturated wicks 10 and through the porous partitions 8 and will become charged with the evaporated liquid and will finally pass around 5 the baffle 15 through the discharge pipe 16 and thence to the point at which it is desired to use the gas.

While the current of air is passing through the receptacle, the beaters 11 are moved into 10 contact with the wicks 10, thereby jolting them so as to remove any excess fluid from the wicks, retard the coalescence of drops, and destroy such drops of volatile fluid that may form on the surfaces thereof. Instead of using air pressure 15 from the inlet pipe, it is possible to operate the apparatus by suction applied to the discharge pipe. This is of advantage when the apparatus is used in connection with an internal combustion engine.

20 As the liquid carried by the absorbent wicks 10 is evaporated, the liquid in the receptacle 2 will keep the wicks saturated by capillary attraction. As the level of the liquid in the receptacle is lowered, a fresh supply will flow into 25 the receptacle from reservoir 18 through pipe 19. The apparatus is thus automatically supplied with fluid in exact proportion to the amount evaporated and due to capillary attraction and the action of the beaters 11, the absorbent wicks 30 will be kept at a uniform degree of saturation so that a gaseous mixture of uniform richness will be produced and the apparatus will function without any further supervision.

While I have described the apparatus as suitable for use with air, it is obvious that other fluids may be used instead of air. The term "air" has been employed as a convenient term of expression and is not intended to limit the use of this invention to the employment of air 40 only, as any desired gaseous medium is contemplated.

45 My invention provides a convenient, safe, inexpensive, and durable apparatus for enriching a gas with desired vapors and will and can be used to great advantage wherever a supply of gas of uniform richness and superior qualities is desired.

I claim:

1. In a carburetor, an enclosed receptacle for 50 a volatile liquid, an air inlet, a vapor outlet, a plurality of transverse partitions of absorbent material extending into the liquid, a transverse partition of pumice stone, succeeding the partitions of absorbent material and means adjacent 55 the air inlet whereby incoming air is passed beneath the surface of the liquid, said pumice stone partition extending into the liquid.

2. In a carburetor, an enclosed receptacle for 60 a volatile liquid, an air inlet, a vapor outlet, a plurality of transverse partitions of absorbent material extending into the liquid and a plurality of partitions of pumice stone, one of said last mentioned partitions being located adjacent the vapor outlet.

3. In a carburetor, a reservoir for holding volatile liquid, an air inlet, a vapor outlet, a plurality of transverse partitions of absorbent material extending part way into the liquid, and

a beater adjacent each of said transverse partitions.

4. In a carburetor, a reservoir for holding volatile liquid, an air inlet, a vapor outlet, a plurality of transverse partitions of absorbent material extending part way into the liquid, a beater adjacent each of said transverse partitions, and a transverse partition having very fine openings therethrough.

5. Apparatus of the class described, comprising an enclosed receptacle, an inlet at one end thereof, and an outlet at the other end thereof, and a succession of transverse partitions in the receptacle between the inlet and the outlet, some of the partitions being of a fibrous absorbent 15 nature and others being of a porous stone-like character, one of the latter partitions being arranged adjacent the outlet, the others being interspersed between the fibrous partitions, the receptacle being adapted to retain a body of volatile liquid in the bottom thereof and all of said partitions being vertical and adapted to 20 extend below the level of the liquid.

6. In a carburetor, an enclosed receptacle for 25 a volatile liquid, an air inlet, a vapor outlet, a plurality of transverse partitions of absorbent material extending into the liquid, a plurality of partitions of pumice stone, one of said last 30 mentioned partitions being located adjacent the vapor outlet, and a baffle adjacent the vapor outlet.

7. A carburetor, comprising an air inlet, a receptacle having therein a layer of volatile liquid, a partition of pumice stone whereby the gas 35 is broken up into finely divided particles, and means adjacent the air inlet whereby the incoming air is passed beneath the surface of the liquid.

8. In a carburetor, a reservoir for holding volatile liquid, an air inlet, a vapor outlet, a plurality of transverse partitions of absorbent material 40 extending part way into the liquid, a beater adjacent each of said transverse partitions, and a baffle adjacent the vapor outlet.

9. Apparatus of the class described, comprising an enclosed receptacle, an inlet at one end thereof, and an outlet at the other end thereof, a succession of transverse partitions in the receptacle between the inlet and the outlet, some of the partitions being of a fibrous absorbent 50 nature and others being of a porous stone-like character, the last partition of the series nearest the outlet being of the latter type, and a beater adjacent each of said fibrous partitions.

10. Apparatus of the class described, comprising an enclosed receptacle having separated air inlet and vapor outlet passages to the liquid in the receptacle, spaced apart partitions disposed between the inlet and outlet passages and extending below the level of the liquid for successively breaking up the air into irregular and indeterminate tiny streams, an absorbent element of a wick-like character arranged between said partitions, and means adjacent the air inlet whereby the incoming air is caused to pass beneath the surface of the liquid.
